VENETIAN BLIND DUSTING BRUSH

Filed May 10, 1948

UNITED STATES PATENT OFFICE

2,552,366

VENETIAN BLIND DUSTING BRUSH

Harold Simon Bush, San Antonio, Tex.

Application May 10, 1948, Serial No. 26,021

1 Claim. (Cl. 15—210)

1
This invention relates to a brush adapted for dusting or cleaning Venetian blind slats.

An object of this invention is to provide a brush embodying a pair of brush elements which are engageable on opposite sides of a Venetian blind slat and movable lengthwise of the slat so as to clean both sides of the slat in one operation.

Another object of this invention is to provide a pair of brush members with a handle projecting from each member, one of the handles being relatively rigid with the other handle yieldable, so that the desired pressure may be applied to the brush members.

A further object of this invention is to provide a brush of this kind wherein the brush heads may be removed for cleaning or replacement.

With the above and other objects in view, my invention consists in the arrangement, combination and details of construction disclosed in the drawings and specification, and then more particularly pointed out in the appended claim.

In the drawing,

Figure 1 is a plan view of a brush constructed according to an embodiment of this invention,

Figure 2 is a sectional view taken on the line 2—2 of Figure 1,

Figure 3 is a fragmentary sectional view taken on the line 3—3 of Figure 1,

Figure 4 is a sectional view taken on the line 4—4 of Figure 2.

Referring to the drawing, the numerals 10 and 11 designate generally a pair of brush members which are disposed with their heads in confronting relation so that they may be engaged on opposite sides of a Venetian blind slat. The brush member 11 includes a holder 12 of channel-shape, which has extending from the center thereof an elongated handle 13 which is relatively rigid. In the present instance the handle 13 is secured to the holder 12 by fastening means 14 but it will be understood that where the holder 12 and the handle 13 are formed of plastic or similar material the handle and holder may be formed as an integral unit.

The holder 12 has removably mounted therein a brush head generally designated as 15. The brush head 15 includes a relatively rigid back member 16 which engages in the holder 12 and in the present instance the head 15 is formed of sheep's wool 17 and the skin 18, the latter being fixed in any suitable manner to the back 16. It will be understood that the brush head 15 while herein disclosed as being formed of sheep's wool, may be constructed of any suitable material, 55 particles from the brush heads.

2
synthetic or natural, the use of sheep's wool being only one example of a brush head for use with the holder 12.

The brush member 10 includes a channel-shaped holder 19 which has mounted therein a brush head generally designated as 20. The head 20 includes a relatively rigid back member 21 engageable in the holder 19, and a brush element formed of sheep's wool 22 and including the skin 23 is secured to the back 21 and is disposed with the fibers in confronting position to the fibers 17. The holder 19 has secured thereto an elongated resilient handle generally designated as 24, which is formed of a resilient wire twisted 10 upon itself between the ends thereof, as indicated at 25. The handle 24 includes a pair of divergent members 26 formed with eyes 27 which are secured to the holder 19 by fastening means 28. While the fastening means 28 is herein disclosed as being short screws or the like, it will be understood that these fastening means may be rivets, grommets or other suitable fastening means, and where the holder 19 is formed of metal, the divergent ends 26 of the handle 24 15 may be welded or otherwise firmly secured to the holder 19.

The handle 24 includes at its rear end an elongated loop 29 adapted to overlie the flat upper surface 30 of the handle 13 and a bolt 31 carried by the rear portion of the handle 13 extends 20 through the loop 29. A wing nut 32 is threaded onto the bolt 31 and is adapted to clamp the loop 29 onto the handle 13. As disclosed in Figure 2, the handle 24 is longitudinally bowed so that the confronting faces of the brush members 10 and 11 will be disposed in parallelism and so that when the two handles are grasped in one hand, the resilient handle 24 may be pressed toward the rigid handle 13 so as to thereby place the two 25 brush members under the desired pressure for wiping or cleaning the opposite sides of the Venetian blind slat.

In the use of this brush structure, the slat is 30 interposed between the two brush members 10 and 11 and the brush members are then moved lengthwise along the slat. The two handles 13 and 24 are grasped in one hand and pressure is applied to the two brush members by squeezing the handles toward each other, the resilient handle 24 bending inwardly toward the rigid handle 13. The brush heads may be partially cleaned 35 by loosening the wing nut 32 and swinging the brush heads away from each other and then shaking or otherwise loosening the dust or dirt 40 particles from the brush heads.

In the event it is desired to more thoroughly clean the brush heads, these heads may be removed from the holders by endwise movement which will disengage the backs 16 and 21 from the holders 12 and 19 respectively. The brush heads can be renewed where the fibers or bristle structure is worn or unduly compacted, it being only necessary to slide the new brush heads into the holders 12 and 19.

I do not mean to confine myself to the exact details of construction herein disclosed, but claim all variations falling within the purview of the appended claim.

What I claim is:

A Venetian blind dusting brush comprising a pair of confronting brush heads, a channel shaped holder for each head, a relatively rigid handle fixed at one end to one of said holders, a resilient longitudinally bowed twisted wire handle including divergent integral members on one end thereof fixed to the other of said holders on its outer face, a loop formed on the other

end of said resilient handle, and releasable fastening means comprised of a bolt extending through said loop and into said rigid handle and a wing nut for securing said handles together.

HAROLD SIMON BUSH.
